By

UNITED STATES PATENT OFFICE.

WILLIAM E. WINE, OF TOLEDO, OHIO.

CAR HOPPER AND LOCKING MEANS THEREFOR.

Application filed January 10, 1922. Serial No. 528,247.

To all whom it may concern:

Be it known that I, WILLIAM E. WINE, a citizen of the United States of America, residing at Toledo, in the county of Lucas and 5 State of Ohio, have invented certain new and useful Improvements in Car Hoppers and Locking Means Therefor, of which the following is a specification.

My invention relates to new and useful 10 improvements in hopper cars and especially to the hopper, hopper door and the means for supporting and locking the latter.

One of the objects of the present invention is to provide a hopper construction in which 15 the door for closing the discharge opening of the hopper is below the general floor line of the car, and to provide a door of strong and simple construction which may be reinforced by standard flanged sections, preferably in the form of angle irons, extending 20 beyond the outer end of the door to form ledges for cooperating with supporting hooks pivotally secured to the side of the car body.

25 A principal feature of the invention consists in reinforcing the door by a plurality of angle irons secured to the outer face thereof and extending toward and being secured to hinge members by which said door is movably connected to an adjacent center 30 sill of the car, the said angle irons each having one flange disposed substantially parallel to the plane of the door and having its other flange disposed at an angle thereto, 35 hooks pivotally mounted upon the outer side of the car being provided for engaging the angle irons to support the door in closed position.

Another feature of the invention consists 40 in providing the car with a hopper formed by placing the hinged door for the hopper at a point below the general floor line such that the hopper terminates above the bottoms of the car sills between which it is located a distance sufficient to permit the hinged door to be provided on its under side 45 with flanged reinforcing members adapted to extend under and project outwardly beyond the neighboring side sill of the car so

as to afford seats or ledges for cooperating 50 with pivotally mounted hooks carried upon the outer side of the car body.

Other features of the invention, residing in certain novel arrangements and combinations of parts, will hereinafter appear and 55 be pointed out in the claims.

Referring now to the drawings showing a preferred embodiment of the invention,

Fig. 1 is a side elevation showing the forward edge of a car door, the locking hooks 60 and a fragmentary portion of the side of a car.

Fig. 2 is a cross sectional view, showing one door, portions of a center sill and of a side sill, the outer frame work of the car and 65 the locking device, the dotted lines showing the door in a dropped position.

It is to be understood at the outset that although I have shown the door and the locking device as applied to a freight car, 70 the invention might equally be applied to other structures calling for a drop bottom door.

In the drawings, a type of car is shown 75 having upright stakes 1 and diagonal braces 3 of well known form. The ordinary floor of the car is shown at 4, while 5 indicates one of the center sills and 6 is the side sill adjacent thereto. The hoppers which are arranged on opposite sides of the center sills 80 inwardly of the corresponding side sills are formed by hopper planks 7 extending downwardly below the car floor and terminating above the lower edges of the center and side sills 5 and 6, respectively.

85 The center sill 5 is preferably formed as a flanged member of channel shape, and the adjacent side sill 6 is likewise preferably constructed as a channel iron. The flanges of these sills extend toward each other. Secured to the web of the center sill 5 between the flanges at the top and bottom of said sill are hinged brackets 9 for cooperating with hinged members 10 carried by the door 11.

90 The door, which is adapted to swing to open position under the influence of gravity, is provided upon its under or outer side with a plurality of door arms 13 to the inner ends

of which the hinges 10 are preferably firmly bolted. The door arms 13 may advantageously be angle irons each of which has one flange abutting and secured to the under 5 surface of the door, the other flanges of said angle irons being disposed in planes normal to the door so as to efficiently stiffen the latter. The outer ends of the angle iron door arms 13 are adapted to extend under 10 the lower flange of the side sill 6 so as to project beyond the outer side of said sill when the door is in closed position. The horizontal flanges of the portions of the angle irons 13 which project beyond the free 15 edge of the door and beyond the outer side of the car form seats or ledges 15 adapted to be seated upon supporting hooks 16.

The hooks 16 are pivotally mounted upon the outer side of the car and their lower 20 ends extend downwardly below the bottom of the adjacent side sill 6. The hooks are preferably supported against lateral strains by means of overlying brackets 17 riveted to the outer face of the car side sill; and 25 pivoted locking cams or dogs 18 adapted to engage said hooks may be employed for preventing the latter from accidentally swinging to a position permitting the door to open. It is advantageous to arrange the 30 hooks 16 so that, as shown in the drawings, they face in opposite directions, for when the oppositely extending legs or flanges 15 of the angle iron door arms are engaged by the hooks and the cams 18 are rotated to 35 position for preventing releasing movements of the hooks, a lateral shifting movement of the door both forwardly and rearwardly will be effectually prevented.

To close the door 11 it is only necessary 40 to raise it until the hooks 16 can be swung under the ledges 15 of the angle iron door arms 13. When the hooks have thus been brought into supporting relation to the door arms the locking cams 18 are rotated and 45 forced against the rear edges of the hooks with which they are respectively associated, thus preventing accidental release of the latter.

By my invention a very inexpensive hopper construction is provided wherein the door for closing the discharge opening of the hopper is well protected against accidental injury and at the same time is located sufficiently close to the rail to render its closing by hand easier than would be the case if it were located at the normal floor height. It will be perceived that the door is strongly reinforced by the angle irons which 50 cooperate with the hooks to support the door, and that the rear ends of the supporting angle irons also provide reinforcements for the hinges.

Many slight changes may be made without in any way departing from the spirit 60 and scope of the invention.

Having thus described the invention, what I claim as new and desire to secure by Letters Patent is:

1. In combination with a freight car having center and side sills and a hopper located between the adjacent center and side sills, of a hinged door for closing the discharge opening of said hopper, and means movably mounted on the outer side of the car side sill for releasably supporting said door in closed position, the lower end of said hopper being above the bottoms of the said sills between which it is disposed, and said door having rigidly secured to the outer face thereof an arm projecting beyond the free edge of the door and adapted when said door is closed to extend under the adjacent side sill of the car in position to be supportingly engaged by said means for supporting said door in closed position. 70 75 80 85

2. In combination with a freight car having center and side sills and a hopper located between adjacent center and side sills, of a hinged door for closing the discharge opening of said hopper, and means pivotally mounted on the outer side of said car for releasably supporting said door in closed position, the lower end of said hopper being above the bottoms of said sills between which it is disposed, said sills between which said hopper is arranged having flanges extending toward said door, said door being hinged to the adjacent center sill above the bottom of the latter, and said door having secured to the outer face thereof means adapted to extend under the adjacent side sill of the car in position to be supportingly engaged by said pivotally mounted means for supporting said door in closed position. 90 95 100 105

3. In combination with a freight car having center and side sills and formed with a hopper located between adjacent center and side sills, of a hinged door for closing the discharge opening of said hopper, and a plurality of hooks pivotally mounted on the outer side of said car for releasably supporting said door in closed position, the lower end of said hopper being above the bottoms of said sills between which it is disposed, said sills between which said hopper is arranged having flanges extending toward each other, said door being hinged to the adjacent center sill above a flange with which the latter is provided, and said door having rigidly secured to the outer face thereof a plurality of flanged members which are adapted to extend under the adjacent side sill of the car in position to be respectively engaged by said pivotally mounted hooks. 110 115 120 125 130

4. In combination with a freight car having flanged center sills and provided with a hinged door adapted to swing to open position under the influence of gravity, said

door being hinged to an adjacent center sill below a flange on the latter extending toward said door, a flanged door-arm secured to the outer face of said door and extending outwardly beyond the free edge thereof and beyond the outer side of the car, said door-arm having at its outer end a flange extending substantially parallel to the plane of said door and having a flange disposed at an angle thereto, and a hook 10 pivotally mounted on the outer side of said car and adapted to swing into supporting engagement with the said flange of the door arm which is parallel to the door.

In testimony whereof I affix my signature.

WILLIAM E. WINE.
